CLAIM

The ornamental design for a corner stay for a box, as shown and described.

DESCRIPTION

FIG. 1 is a left side elevational view of a corner stay for a box showing my new design;

FIG. 2 is a top front perspective view thereof;

FIG. 3 is a bottom rear perspective view thereof; and

FIG. 4 is a bottom plan view thereof.

This invention is directed at a corner stay for a box of my new design. The corner saver is placed over the top edge of the corner of a box or the like and pressed together in order to protect the corner from separating or to repair a damaged corner.

FIG. 1

FIG. 4

FIG. 2

FIG. 3
